4 Claims. (Cl. 89—47)

1

This invention concerns improvements in or relating to breech loading mechanism for ordnance.

Various devices are already known for automatically ramming shells into the breeches of guns, some being hydraulically operated and some electrically operated. Hand ramming devices are also known in which the shell after being placed in the loading tray is carried by the moving tray when the latter is swung in front of the breech so as to be in alignment with the breech. In certain constructions a carriage, arranged to travel along a track located at the side of the semi-circular shell guide of the loading tray, is provided with a projection which engages the base of the shell and when the carriage is actuated, rams the shell into the breech. Ramming is executed in such a case by means of a cable running over a pulley at the breech end of the gun, so that on pulling the cable the carriage is moved up the track and rams the shell home. The carriage is returned to its original position either by a second cable or by being slid back by hand, a suitable handle being provided for the purpose. Means are known whereby this system is electrically operated. In this case the cable is attached to the ram in both directions so that pulling on one cable effects the ramming stroke and pulling on the other cable effects the return. The two cables are connected to one shaft and wound round in opposite directions so that by rotating the shaft a suitable number of revolutions first in one direction and then in the reverse direction, a cycle of ramming and return is effected. This shaft is connected up to an electric motor and by suitable switch mechanism together with a reversing switch, automatic ramming is provided.

It is an object of the present invention to provide a power driven ramming device in ordnance of the kind having a loading tray movable between a loading position and a ramming position, such ordnance being referred to hereinafter as "ordnance of the kind described."

According to the invention there is provided in breech loading mechanism for ordnance of the kind described, a carriage arranged to be reciprocable along a guide track on the loading tray and adapted to act as a ram to propel a cartridge or shell into the breech on the forward stroke, a source of power (e. g. an electric motor) mounted at a position remote from said loading tray, and a mechanical coupling between the source of power and the carriage, said coupling including a flexible shaft.

The flexible shaft may be connected to a gear-wheel rotatably mounted on the carriage and geared to a rack which is fixed relatively to the guide track. The invention is not, however, limited to a direct connection between the flexible

2

shaft and the carriage for, providing the flexible shaft is included in the driving devices, the advantages set forth below are obtained. Means may be provided for arresting the carriage at the end of each movement along the guide track, comprising an arrangement for cutting off the power drive to the carriage, and buffers on said carriage.

Where an electric motor is employed, the means for arresting the carriage may comprise regenerative braking.

By such an arrangement, several important advantages are obtainable. By mounting the source of power at a point other than on the loading tray, the weight of the latter is kept down, the number of electric cables movable with the tray is kept low, both of which features are important for efficient operation of the ordnance, and further, the employment of a flexible shaft provides a resilient drive and acts to reduce the shock on the motor and other parts at the beginning and end of a stroke of the carriage. Thus the present invention provides a device which is simple and reliable and easy to maintain.

One example of a breech loading mechanism made in accordance with the present invention for use with 3.7" anti-aircraft guns will now be described with reference to the accompanying drawings in which:

Figure 1 is an elevation of the breech end of the gun showing the loading tray, motor and flexible drive.

Figure 2 is a plan of the tray member.

Figure 3 is a plan view, on a larger scale, of the carriage and associated parts, partly broken away.

Figure 4 is a view of Figure 3 in the direction of the arrow A and partly in section.

Figure 5 is a diagram of the electric circuit and certain mechanically operated parts for controlling the same, said figure indicating in solid lines the positions of the parts at the end of the ramming stroke.

Like reference numerals refer to like parts throughout the several figures of the drawings.

Referring to the drawings: the loading tray 1 of the gun is arranged to swing on an axis 2 parallel to the gun barrel 3 and is movable between two angular positions, one being the loading position and the other being the ramming position. In the latter position the shell in the tray is in alignment with the barrel. The loading tray is provided with a shell guide 4 of semi-circular cross-section. At the side of this semi-circular

shell guide there is a channel 5. A toothed rack 6 is provided in the channel extending along the length of the channel and a carriage 7 provided with side rollers 8 and a top roller 9 is arranged to run along a guide member 20 fixed in the channel and to be confined to movement along

the channel. In Figure 3 the rack 6 is broken away for clearness, the parts being connected by the pitch line. An intermediate gear wheel 10 is rotatably mounted on the carriage and is adapted to mesh with the teeth of the toothed rack. This gear wheel is driven by another gear wheel 11 from an electrical motor 12 which is coupled to a shaft 13, mounted on roller bearings fitted in the carriage 7, and on which the gear wheel 11 is mounted, through a flexible cable drive 14. This drive comprises a steel cable 15 enclosed within a thick rubber tube 16, the cable and rubber tube being coupled to the rotating and non-rotating parts respectively of the carriage and motor as the case may be. The actual coupling is not in itself new and any convenient construction can be used for the purpose. The carriage 7 is provided with a rammer head 22, Figure 2, which engages the base of the shell.

Buffers 17 are fitted on the carriage and furnished with a spring 18. The buffers help to arrest the carriage at each end of its movements by striking against abutments suitably located on the loading tray.

The electrical motor 12 may be mounted in any suitable position on the gun mounting and, as shown, is fixed on the counterpoise and suitable switch means, mounted on the motor, is provided to cause the motor, when the switch is operated, to turn the requisite number of revolutions sufficient to drive the carriage the necessary distance for effecting the ramming and then automatically to stop the motor.

Referring to Figure 5, the electrical circuit comprises a throw-over switch TO which is adapted to make contact alternately with terminals on one or the other of two paths which form parts of alternative circuits. One of these circuits is for the ramming stroke and the other for the return stroke. This throw-over switch is mounted on the loading tray and when the tray enters the ramming position engages a contact on the ramming circuit and when in the loading position engages a contact on the return circuit. Associated with each of these alternative circuits there is also a mechanically operated limit-switch RmL and RrL respectively and there is also provided a switch attached to the usual tray release catch 23 and marked TRS. The limit-switches RmL and RrL are brought into operative condition for the respective strokes by contacts which are made and broken as necessary by the movements of the arms of the switch TO though they do not form part of the main circuits controlled by this switch. The switch TRS is so arranged that when the tray release catch 23 is actuated to lock the tray in either of its two positions the contacts are closed. The limit-switches appertaining to the two alternative circuits may be of any known type and are normally held in a closed position. The contact made by these limit-switches is arranged to be broken when the motor has rotated the necessary number of times to cause the carriage to complete the ramming or return stroke as the case may be. In the example described, the parts are geared up so that the motor rotates 10 revolutions for the ramming stroke and 10 revolutions for the return stroke. In 10 revolutions of the motor a cam 24 geared to the motor shaft rotates half a revolution. The cam is mounted on a worm-wheel 25 which is driven by a worm 26 on the motor shaft, the reduction ratio being 20:1. This cam is arranged at the end of half a revolution to break the appropriate limit-switch. When the loading tray is in the ramming posi-

tion the throw-over switch makes contact with the terminal in the ramming circuit. The circuit is not, however, completed until the hand operated switch TRS is actuated. This is done by the operator after he has swung the tray into the ramming position and allowed the catch of the locking device to engage its notch. The circuit is then completed and the carriage is driven by the motor through the flexible coupling and gear wheels. When the motor has rotated the necessary number of revolutions to cause the carriage to have rammed the shell home, the cam on the worm wheel breaks the limit-switch appertaining to the ramming circuit and the motor and carriage are stopped. The circuit is so arranged that the motor is automatically braked by regenerating braking as described below. The loading tray is then manually swung outwardly to the loading position in readiness to receive the next shell and to allow the breech to be closed and this movement of the loading tray causes the throw-over switch to disconnect the ramming circuit and to connect up to the return circuit. On locking the tray in this position the hand operated switch TRS closes the contacts, the motor rotates in the reverse direction and the return stroke is then completed. The motor is again stopped when the cam on the worm-wheel (or a separate cam if desired) throws out the limit-switch appertaining to the return circuit. It will be evident from the foregoing that the ramming and return circuits are so arranged that the current is reversed through the armature and so the motor rotates in opposite directions for the ramming and return movements. The handles and other parts for manually swinging the tray have been omitted from the drawings as they do not concern the present invention.

As the apparatus is intended for use in the field, the motor, which is preferably compound wound, may be driven by a battery B which, in the example being described, is a 24 volt storage battery. To assist in rapidly stopping the motor at the end of a carriage movement, regenerative braking means is provided, which operates as the appropriate limit-switch is broken. For this purpose, one line from the battery leads to the switch TRS and through the switch to a limit-switch and thence to the coils of a contactor C and a shunt field relay SFR in parallel therewith, to the other line and back to the battery. The first line also passes to the motor through the series field SF and via the switch TO to the armature A and to one contact *a* of the contactor, being tapped between the terminal of the switch TRS and a series field by lines leading to a second contact *b* of the contactor and to one terminal of the shunt field ShF respectively. The other end of the shunt field is connected to one contact *e* of the shunt field relay and the second contact *f* of said relay is connected to the other pole of the battery, being tapped en route for the other ends of the contactor and shunt field relay coils and for a line leading to a third contactor contact *c*. The fourth contactor contact *d* is joined to the first contact. A condenser and resistance are shunted across the shunt field relay contact.

When the switch TRS is turned to the "on" position, e.g. as the tray is locked in the ramming position, the moving contact bar of the contactor is connected to the first and third contacts (i. e. the lower pair in Figure 5), and the shunt field is energised by the shunt field relay so that the motor runs as a compound motor. When the limit-switch RmL is broken as the carriage

reaches the end of the ramming stroke, the contactor bar moves back by spring pressure to the second and fourth contacts *b* and *d* (i. e. the upper pair in Figure 5) and the series field and armature are short circuited. Meanwhile the shunt field is still energised due to the delay action incorporated in the shunt field relay, so that the back E. M. F. of the motor flowing through the low impedance of the armature and series field gives instant and heavy regenerative braking; after a period of say half a second the shunt field relay opens and the shunt field ceases. A similar sequence of events takes place on the return stroke when the tray is locked in the loading position.

Figure 5 illustrates in solid lines the positions occupied by the various parts when the ramming has just been completed, the limit-switch *RmL* has just been broken by the cam *24*, and the contact bar of the contactor has sprung back to the contacts *b* and *d*.

With the exception of the hand operated switch and the throw-over switch the switch arrangements described above are housed in a casing fixed to the motor itself and thus the motor and the limit switch can be located on a part of the gun mounting out of the way. With the construction described above there is only the flexible drive between the motor and the loading tray, and thus there is very little, if any, increase in the weight of the loading tray. It is found a simple matter in practice to arrange the motor at a convenient distance from the ramming carriage so that the flexible cable does not adversely affect the operation of loading or firing the gun.

While the above construction involves the use of a direct current electric motor it will be appreciated that any other suitable source of power may be used for driving the flexible shaft, for example other forms of electric motor or any suitable form of fluid motor.

What I claim as my invention and desire to secure by Letters Patent is:

1. Breech loading mechanism for ordnance of the kind described comprising a loading tray movable between a loading position and a ramming position relative to a gun, a guide track on the loading tray, a carriage arranged to reciprocate along said guide track and adapted to act as a ram to propel a cartridge or shell into the breech on the forward stroke, an electric motor for driving said carriage mounted at a position remote from said loading tray and relative to which the loading tray can move, means for energizing the motor throughout the ramming stroke of said carriage and for automatically de-energizing the motor only after the carriage has completely rammed the cartridge or shell into the breech, and a mechanical coupling between the motor and the carriage, said coupling including a resilient torsional drive means so constructed and operatively connected to the motor and carriage as to reduce the shock on the motor and other parts when the carriage is abruptly brought to a stop at the end of a rapid ramming stroke.

2. Breech loading mechanism for ordnance of the kind described comprising a loading tray movable between a loading position and a ramming position relative to a gun, a guide track on the loading tray, a carriage arranged to reciprocate along said guide track and adapted to act as a ram to propel a cartridge or shell into the breech on the forward stroke, a motor for driving said

carriage mounted at a position remote from said loading tray and relative to which the loading tray can move, a mechanical coupling between the motor and the carriage, said coupling including a resiliently flexible shaft driven by the motor, a rack which is fixed relatively to the guide track, and a gear wheel rotatably mounted on the carriage in geared relation to said rack and operatively connected to the flexible shaft to be driven thereby.

3. Breech loading mechanism for ordnance of the kind described comprising a loading tray movable between a loading position and a ramming position relative to a gun, a guide track on the loading tray, a carriage arranged to reciprocate along said guide track and adapted to act as a ram to propel a cartridge or shell into the breech on the forward stroke, a motor for driving said carriage mounted at a position remote from said loading tray and relative to which the loading tray can move, a mechanical coupling between the motor and the carriage, said coupling including a resiliently flexible shaft driven by the motor, a rack which is fixed relatively to the guide track, and a gear wheel rotatably mounted on the carriage in geared relation to said rack and operatively connected to the flexible shaft to be driven thereby, and means for arresting the carriage at the end of each movement along the guide track, said means comprising means for discontinuing the operation of said motor, and buffers on said carriage.

4. Breech loading mechanism for ordnance of the kind described comprising a loading tray movable between a loading position and a ramming position relative to a gun, a guide track on the loading tray, a carriage arranged to reciprocate along said guide track and adapted to act as a ram to propel a cartridge or shell into the breech on the forward stroke, an electric motor for driving said carriage mounted at a position remote from said loading tray and relative to which the loading tray can move, a mechanical coupling between the motor and the carriage, said coupling including a resiliently flexible shaft driven by the motor, a rack which is fixed relatively to the guide track, a gear wheel rotatably mounted on the carriage in geared relation to said rack and operatively connected to the flexible shaft to be driven thereby, and means for arresting the carriage at the end of each movement along the guide track, said means comprising switch means for cutting off the electric current to the motor and means associated with said motor whereby said motor is operative by regenerative braking for arresting the movement of said motor.

DESMOND WALTER MOLINS.
